US0D1101326S

(12) **United States Design Patent** (10) **Patent No.:** **US D1,101,326 S**
(45) **Date of Patent:** **** Nov. 4, 2025**

(54) **WASHING MACHINE AGITATOR**

(71) Applicant: **Hefei Midea Laundry Appliance Co., Ltd.**, Anhui (CN)

(72) Inventor: **Jianwei Liu**, Anhui (CN)

(73) Assignee: **Hefei Midea Laundry Appliance Co., Ltd.**, Hefei (CN)

(**) Term: **15 Years**

(21) Appl. No.: **35/521,054**

(22) Filed: **Apr. 23, 2024**

(80) **Hague Agreement Data**

Int. Filing Date: **Apr. 23, 2024**

Int. Reg. No.: **DM/237138**

Int. Reg. Date: **Apr. 23, 2024**

Int. Reg. Pub. Date: **May 31, 2024**

(30) **Foreign Application Priority Data**

Nov. 10, 2023 (CN) 202330736751.X

(51) **LOC (15) Cl.** **15-05**

(52) **U.S. Cl.**

USPC **D32/26**

(57) **CLAIM**

The ornamental design for a washing machine agitator as shown and described.

DESCRIPTION

The patent or application file contains at least one drawing executed in color. Copies of this patent or patent application publication with color drawing(s) will be provided by the Office upon request and payment of the necessary fee.

1. Washing machine agitator

1.1: Front

1.2: Back

1.3: Left

1.4: Right

1.5: Top

1.6: Bottom

1.7: Perspective

The portions of the washing machine agitator shown in red overlay form no part of the claimed design.

1 Claim, 7 Drawing Sheets

(6 of 7 Drawing Sheet(s) Filed in Color)
